(57) **CLAIM**

The ornamental design for a rotary cutter guide, as shown and described.

DESCRIPTION

FIG. 1 is a front, perspective view of a rotary cutter guide showing a new design, where the rotary cutter guide is shown attached to a handheld rotary cutter that is depicted by broken lines;

FIG. 2 is a back, perspective view of the rotary cutter guide shown in FIG. 1, where the handheld rotary cutter is not shown;

FIG. 3 is a front view of the rotary cutter guide shown in FIG. 2;

FIG. 4 is a right side view of the rotary cutter guide shown in FIG. 2;

FIG. 5 is a left side view of the rotary cutter guide shown in FIG. 2;

FIG. 6 is a top view of the rotary cutter guide shown in FIG. 2;

FIG. 7 is a bottom view of the rotary cutter guide shown in FIG. 2; and,

FIG. 8 is a back view of the rotary cutter guide shown in FIG. 2.

The broken line showing of the handheld rotary cutter in FIG. 1 is provided for purposes of environment and forms no part of the claimed design.

1 Claim, 2 Drawing Sheets
